UNITED STATES PATENT OFFICE.

ROBERT W. GILPIN AND JOSEPH B. ROMINE, OF CODELL, KANSAS.

DETACHABLE PACKER-RIM FOR HARROW-DISKS.

1,105,130.

Specification of Letters Patent. Patented July 28, 1914.

Application filed October 8, 1912. Serial No. 724,868.

To all whom it may concern:

Be it known that we, ROBERT W. GILPIN and JOSEPH B. ROMINE, citizens of the United States, residing at Codell, in the county of Rooks and State of Kansas, have invented certain new and useful Improvements in Detachable Packer-Rims for Harrow-Disks, of which the following is a specification.

10 This invention relates to improvements in rims for harrow disks.

The primary object of the invention is to provide a rim which may be attached to the periphery of harrow disks, and which may 15 be used as a surface or subsoil packer.

A further object of the invention is to provide a rim disposed to be clamped to the harrow disk, the rim being of such configuration as to resiliently engage the disk when 20 in clamped position, preventing movement of the rim with respect to the disk.

Another object of the invention is to provide a sectional rim, the sections of which are so hinged that the periphery of the rim 25 is not enlarged at the hinged point.

A still further object of the invention is to provide a hinged connection, one of the members of which receive the disk, the disk locking the sections together independent of 30 the means which connect their free ends.

In the drawings, Figure 1 is a perspective view showing the rim arranged on the disk; Fig. 2 is an assembled perspective; Fig. 3 is a transverse section; Fig. 4 is a 35 transverse section through the hinged connection; Fig. 5 is a disassembled perspective view of the members which form the hinge.

In the drawings, 10 designates one section of the rim which is semi-circular, being 40 formed of tubular resilient metal, the inner face of the rim being provided with a groove 11 which receives the harrow disk. The rim is formed in two sections, being preferably constructed of tubular material, the inner 45 face of the sections being formed with grooves 11. The member 10 is formed adjacent the hinged terminal with extensions 21 and 22, which are provided with ears 23 and 24 disposed in opposite directions, the 50 ear 23 being formed from the outer face of the tube and the ear 24 from its inner face, the ears being bent upon the extensions forming bifurcations of double thicknesses of metal, the bifurcations being apertured

to receive the pivot pin 16. In forming the 55 female member of the hinge, the inner and outer portions of the rim are severed and slit twice longitudinally along the inner and outer edges, and the metal bent out to form ears 23 and 24, thus providing the bifurcations 21 and 22. Particular attention is called to the construction of this terminal of the member 10, as it provides a rigid connection formed entirely of the material from which the member 10 is formed. 65

The terminal 14 of the section 15 constitutes the male member of the hinge and is of substantially the same formation as the hinged terminal of the member 10, except that it is formed, as shown in Fig. 5, by 70 severing the inner face transversely, and slitting it longitudinally along one edge. After slitting and severing the metal, as described, the inner edge is bent in to form a groove 26 having a double thickness of metal 75 on each side, as shown in Fig. 5. The tube walls are then pressed inwardly and flattened so as to be of a suitable thickness to enter between the wings 22 and 23. These double walls are perforated to receive a pin 80 16. The extension 14, therefore, comprises four thicknesses of material apertured to receive the pivot pin 16, the four thicknesses being arranged to form spaced double thicknesses of material, producing the 85 groove 26 which is in alignment with the groove 11 of the sections.

In the formation of both the male and female members of the hinge, it is noted that the extensions are formed from the tubular 90 metal which constitutes the rim. It will thus be obvious that the arrangement is such that the hinge does not project beyond the periphery of the sections, which would normally occur, and which would cause a depression in the soil in excess of that caused by the unbroken portion of the sections. 95

Each of the sections is provided adjacent its free end with a bracket which is formed with an upturned apertured terminal, a 100 screw 18 passing through the terminal 17 of the bracket 17 which is supported on the member 10, said screw passing through the terminal 19 of the bracket 19 which is mounted on the section 15. A nut 20 receives the terminal 21 of the screw 18, said nut being formed with a flat face 22 which contacts with the section, the nut in this 105

manner being prevented from rotating. It will be noted that as the screw is rotated, the sections 10 and 15 will be drawn into binding contact with the disk. The sections 5 are sufficiently resilient to be drawn together, securely clamping the sections on the disk and preventing their rotation with respect to the disk. It will be noted by this construction that the rim is effectually held 10 against movement with respect to the disk without the necessity of passing securing devices through the disk.

It will be noted by the peculiar hinged construction heretofore described that should 15 the screw 18 become displaced, the sections will remain on the disk, as it will be impossible to swing the sections on their hinged connection with the disk inserted within the space 26 of the extension 14, it being noted 20 that the disk bridges the space between the sections and effectually locks them against movement. This construction is of a particular advantage as where the rim rotates with respect to the disk, the same readily 25 becomes worn, the sharp periphery of the disk cutting through the rim. In the present construction, it will be noted that the rim will travel at all times with the disk, the sections which form the rim being 30 tightened to compensate for slight variations in the diameter of the disk. It will also be noted that the sections may be readily formed of tubular metal which in being bent to conform to the curvature of the disk may 35 be provided with the groove which receives the periphery of the disk.

It will be noted that while the sections are shown as formed of tubular metal, they may be solid, yet of such design and sufficiently 40 resilient to produce the desired result.

Having thus described our invention, what

we claim and desire to secure by Letters Patent is:

1. A rim for harrow disks formed of tubular sections, one of the sections being 45 formed with longitudinally and transversely disposed slits adjacent one of its terminals to produce ears disposed in opposite directions, said ears being bent upon the portions of the section with which they 50 are formed integral, one of the terminals of the other section being provided with a transversely disposed slit and pressed together to form an extension of less width than the section, said extension being disposed 55 between the ears of the other section, and a pivot pin passing through said ears and said extension.

2. A rim for harrow disks formed of tubular sections each of the sections being 60 formed interiorly with a groove, one of the sections being provided with longitudinal and transverse slits adjacent one of its terminals to produce ears which extend in opposite directions, said ears being bent upon 65 the portions of the section with which they are formed integral, one of the terminals of the other section being formed with a transverse slit and pressed together to form an extension of less width than the section, said 70 extension being disposed between the ears of the other section, and a pivot pin passing through said ears and said extension, said extension being provided with a groove 75 which alines with the groove of the sections.

In testimony whereof we affix our signatures in presence of two witnesses.

ROBERT W. GILPIN. [L. S.]

JOSEPH B. ROMINE. [L. S.]
